CAPSULE

Lloyd Frank Hansen, New City, N.Y.

Application September 25, 1957, Serial No. 47,868

Term of patent 14 years

(Cl. D16—3)

Fig. 1

Fig. 1 is a front elevational view of a capsule, showing my new design;

Fig. 2 is a right side elevational view thereof.

The characteristic features of my new design reside in the figure shown on the surface of the capsule.

The side not shown of the elephant head is similar to the side shown, although the end of the trunk appears on the shown side only.

I claim:

The ornamental design for a capsule, substantially as shown and described.
